CARD POSITIONING MEANS

Albert E. Long, Chicago, Ill., assignor to Stromberg Electric Company, Chicago, Ill., a corporation of Delaware

Application May 17, 1930, Serial No. 453,261

9 Claims. (Cl. 234—43)

My invention relates to card positioning means for time recorders.

In a certain type of time recorder, a card receiver is provided into which the workman may insert his time card, time controlled means being provided for variably limiting the distance to which the card may be inserted so that at a predetermined time the distance to which the card may be inserted will be automatically changed. This automatic changing of the distance to which the card may be inserted may correspond in some instances to a definite program under which the plant operates. For instance, a change might be made immediately after the time at which the workmen are presumed to leave for the noon hour and another which might be made immediately after the time at which the workmen are presumed to have returned from the noon intermission. It will occasionally happen, of course, that a workman may be leaving for the noon intermission after the shift has been made from "noon out" to "noon in" in which case it is desirable that some manual means may be provided whereby the distance to which the workman's card may be inserted will correspond to "noon out" rather than to "noon in". Other analogous situations may arise in which it may be desirable to have manual control for the card insertions.

One of the objects of my invention is to provide an improved construction whereby the desired results indicated above may be accomplished. Further objects will appear from the description and claims.

In the drawings, in which an embodiment of my invention is shown:

Fig. 1 is a vertical sectional view from the front showing my improved card receiver and associated parts;

Fig. 2 is a section on the line 2—2 of Fig. 1 showing the time controlled stepped limiting means in operative relation to the card;

Fig. 3 is a section also on the line 2—2 of Fig. 1 showing the manually controlled stepped member in operative relation to the lower edge of the card;

Fig. 4 is a perspective view of the two alternatively usable stepped members;

Fig. 5 is a rear view of the pivoted card rest; and

Fig. 6 is a plan view of the pivoted card rest. Referring to the drawings in detail, the construction shown comprises a pair of spaced card guides 1 for receiving the opposite edges of the inserted card 2 respectively and guiding it to proper printing position, spaced time controlled printing wheels 3 against which the card 2 is

snapped by the action of the printing hammer 4, a ribbon 5 traveling between the printing wheels 3 and the card 2, and time controlled means for limiting the distance to which the card 2 may be inserted.

The time controlled means for limiting the distance to which the card may be inserted comprises a pair of stepped members 6 each having a series of steps 7 successively brought into card engaging position, a pivoted frame 8 on which the pair of stepped members 6 is mounted, and a time controlled cam 9 engaging a pin 10 on the pivoted frame 8 for causing a step by step pivotal movement of the pivoted frame 8 to bring the steps 7 successively into position to be engaged by the inserted cards. An electric mechanism (not shown) is provided for causing a periodic step by step movement of the spiral cam 9, a light spring (not shown) being provided to insure that the pin 10 will remain in engagement with the edge of the spiral cam 9. Each step by step movement of the spiral cam 9 is just sufficient to permit a one-step movement of the pivoted frame 8 to bring the next lower steps of the stepped members 6 into position for engagement with the lower edge of the inserted card 2.

In order to enable a manual control of the distance to which the card 2 may be inserted, which manual control shall be to some extent independent of the time controlled movement, each of the step members 6 has slidably mounted thereon another stepped member 11 which may under certain conditions be brought into operative relation to the inserted card 2 in place of the steps on the time controlled stepped members 6. The slidably mounted step member 11 is guided in its movement by means of a pair of pins 12 secured to the step member 6 extending through a pair of slots 13 and 14, respectively, in the slidable step member 11 and a pin 15 secured to the slidable step member 6 and movable in a slot 16 in the time controlled step member 6. The sliding movement is such that when the slidable member 11 is in its lowermost position the steps on the time controlled step member 6 will be operative to determine the distance to which the card is inserted but such that when the slidable step member 11 is in its uppermost position the steps 17 on the slidable member 11 will be the ones which determine the distance to which the card 2 is inserted and will support the card 2 one step higher than would be the case if the slidable step member 11 were in its lowermost position.

For operating the slidable step members a rock

110

- shaft 18 is provided having secured thereto a rock plate 19 extending between the slideable step members 11 and engaging the lower edges thereof so that when the rock plate 19 is moved from the 5 position shown in Fig. 2 to the position shown in Fig. 3 the change of the rock plate will cause the slideable stepped members 11 to be moved from the lowermost position shown in Fig. 2 to the uppermost position shown in Fig. 3.
- 10 For operating this rock shaft a manually operable lever 20 is provided pivotally mounted at 21 and having pivotally secured at its rear end a link 22 which extends downwardly and has its lower end secured to a rock arm 23 on the rock 15 shaft. In order to limit the distance to which the manually operable lever may be moved and thus prevent undue strain on the slideable stepped members and associated parts, a link 24 is provided pivotally secured to the lever 20 at 25 and 20 having a slot 26 therein through which extends a fixed pin 27.

In order that the slideable stepped members may not be operated except when authorized, a lock bolt 28 may be provided underneath the outer end of the operating lever 20 so that the operating lever 20 cannot be depressed to raise the stepped members until this lock bolt is withdrawn from underneath the operating lever by the proper authority.

- 30 Referring further to the details of construction the frame members 8 may be mounted on a rock shaft 9 and in turn mounted in the side frames 29^a of the recorder. The right-hand stepped member 6, as seen in Fig. 5, may be 35 mounted in various positions on the cross member 29 to accommodate different widths of cards. For this purpose the cross member 29 is provided with a series of slots 30 into any one of which the web portion of the member 6 may be 40 inserted. The member 6 may be held on the cross bar 29 by any suitable means, such as a securing screw 31.

In use, if a situation arises in which it is desired that the card 2 may be inserted only far 45 enough to correspond to the position previous to the last shifting movement of the pivoted frame 8, the workman will arrange with the foreman for the unlocking of the lock bolt 28. The workman can then press the lever 20, which will raise 50 slideable stepped members 11 to bring the steps 17 into effective position and limit the distance to which the card will be inserted by an amount equal to one of the steps.

Thus, if the workman happened to be leaving 55 for the noon intermission after the time controlled shift had been made from "noon out" to "noon in" the workman, by raising the stepped members 11, would so limit the distance to which the card 2 might be inserted that the printing would 60 take place in the proper space for "noon out", regardless of the fact that the time shift had been made to "noon in".

While I have shown but one embodiment of 65 my invention, it is obvious that it may be embodied in other forms, as defined by the appended claims.

I claim:

1. In a time recorder, time printing means, card receiving means into which a card may be inserted for printing thereon, time controlled means for variably limiting the distance to which the card may be inserted in said card-receiving means so that at the predetermined time the distance to which the card may be inserted will be changed 70 automatically, and manually controllable means 75 automatically, and manually controllable means

for varying the distance to which the card may be inserted in said same card-receiving means from that determined by the time-controlled means.

2. In a time recorder, time printing means, card receiving means into which a card may be inserted for printing thereon, time controlled means for variably limiting the distance to which the card may be inserted in said card-receiving means so that at the predetermined time the distance to which the card may be inserted will be changed automatically, and manually controllable means for limiting the distance to which the card may be inserted in said same card-receiving means from that determined by the time-controlled means, said time controlled varying means comprising a pivoted member having a series of steps successively brought into card engaging position.

3. In a time recorder, time printing means, card receiving means into which a card may be inserted for printing thereon, time controlled means for variably limiting the distance to which the card may be inserted so that at the predetermined time the distance to which the card may be inserted will be changed automatically, and manually controllable means for limiting the distance to which the card may be inserted, said time controlled limiting means comprising a pivoted member having a series of steps successively brought into card engaging position and said manually controllable means comprising a member movably mounted on said pivoted member having a series of steps which may be brought into operable relation to the card in place of the steps on the pivoted member.

4. In a time recorder, time printing means, card receiving means into which a card may be inserted for printing thereon, time-controlled means for variably limiting the distance to which the card may be inserted in said card-receiving means so that at the predetermined time the distance to which the card may be inserted will be changed automatically, and manually controllable means for varying the distance to which the card may be inserted in said same card-receiving means from that determined by the time-controlled means.

5. In a time recorder, time printing means, card receiving means into which a card may be inserted for printing thereon, time-controlled means for variably limiting the distance to which the card may be inserted in said card-receiving means so that at the predetermined time the distance to which the card may be inserted will be changed automatically, and manually controllable means for varying the distance to which the card may be inserted in said same card-receiving means from that determined by the time-controlled means, said time-controlled limiting means comprising a pivoted member having a series of steps successively brought into card-engaging position.

6. In a time recorder, time printing means, card receiving means into which a card may be inserted for printing thereon, and time-controlled means for variably limiting the distance to which the card may be inserted so that at the predetermined time the distance to which the card may be inserted will be changed automatically, comprising a rock member movable step by step to different positions and a control member mounted on said rock member and engageable by the card in its different positions.

7. In a time recorder, time printing means,

- card receiving means into which a card may be inserted for printing thereon, and time-controlled means for variably limiting the distance to which the card may be inserted so that at the 5 predetermined time the distance to which the card may be inserted will be changed automatically, comprising a rock member movable step by step to different positions and a control member mounted on said rock member and engageable 10 by the card in its different positions, said control member having an arcuate cam portion concentric with the rock member and a rock member engageable with said arcuate cam portion in said different positions.
- 15 8. In a time recorder, time printing means, card receiving means into which a card may be inserted for printing thereon, time-controlled means for variably limiting the distance to which the card may be inserted in said card-receiving 20
- means so that at the predetermined time the distance to which the card may be inserted will be changed automatically, and manually controllable readily returnable means for varying the distance to which the card may be inserted in said same card-receiving means from that determined by the time-controlled means.
9. In a time recorder, time printing means for printing on a card, time-controlled means for variably positioning the card with respect to said time printing means so that at a predetermined time the printing position on the card will be changed automatically, and manually controllable means for variably positioning the card with respect to said same time printing means for changing the printing position on the card from that determined by the time-controlled means.
